CLAIM

The ornamental design for whimsical, bottle-cap-appearance, linear-measurement workpiece gripping device, as shown and described.

DESCRIPTION

FIG. 1 is a front, isometric view showing our new ornamental design for a whimsical, bottle-cap-appearance, linear-measurement workpiece gripping device.

FIG. 2 is a rear, isometric view showing our new design.

FIG. 3 is a single-side elevation of our new design, all side elevations having the same appearance.

FIG. 4 is a front elevation of our new design; and,

FIG. 5 is a rear elevation of our new design.
